UNITED STATES PATENT OFFICE.

JOHN H. RIGBY, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHOE-TREATING MACHINE.

1,412,894.

Specification of Letters Patent. Patented Apr. 18, 1922.

Application filed April 3, 1919. Serial No. 287,110.

To all whom it may concern:

Be it known that I, JOHN H. RIGBY, a citizen of the United States, residing at Beverly, in the county of Essex and State of Massachusetts, have invented certain Improvements in Shoe-Treating Machines, of which the following description, in connection with the accompanying drawings, is a specification, like reference characters on the drawings indicating like parts in the several figures.

This invention relates to machines for treating shoes and more particularly to mechanism for controlling the pressure between the shoe and tool as they are relatively moved. Such mechanism possesses special advantages in connection with automatic burnishing or edge setting machines and as herein described is associated with such machine, but certain aspects of the present invention may be advantageously employed in other machines for treating shoes.

In automatic burnishing or edge setting machines of the general type mentioned, the shoe is ordinarily held by or clamped on a jack and presented to the tool which is moved over or along the surface of the shoe to be treated by automatically produced relative movement between the tool and the work, and means are provided for producing pressure between the work and tool as they are relatively moved. The pressure between the work and the tool, however, is liable to vary along different portions of the work owing to the varying curvature of the surface treated by the tool and such variations of pressure as do occur are unrelated to the necessities of the work and consequently are productive of non-uniform results throughout the treated portions of the shoe, and, in some cases, impair or injure certain portions of the work. The lateral or side portions of the forepart edge of a shoe are nearly flat or straight from the side extremity of the toe curve to the ball, the toe is much more abruptly curved and in some extreme styles may be quite sharp, while the contour from the forepart to the shank presents a more or less abrupt reverse curve. In "spade shank" shoes, for instance, there is a comparatively sharp corner at the junction of the forepart and shank which is liable to be crushed or deformed by

the tool, because at this point the shoe sole is not able to stand the pressure found desirable between the shoe and tool along other portions of the shoe.

An important feature of the present invention, therefore, consists in means, which at a predetermined part of the shoe, acts in opposition to the pressure producing means to control the pressure between the shoe and tool and adapt it to the requirements of the shoe.

As the shoe and tool are automatically moved relatively to present different portions of the shoe to the action of the tool, permissive following movement of the tool toward and from the work is obtained by the yielding action of the pressure producing spring usually employed as a convenient form of yielding pressure means. Such movement of the tool, however, causes variations in the pressure between the work and the tool and, perforce, non-uniform effects on the work. Another important feature of the present invention, therefore, consists of novel means for automatically controlling the pressure producing spring to maintain substantially uniform pressure between the work and tool.

The present invention also comprises various novel features and combinations of parts in addition to those recited, all of which will be fully described hereinafter and for which protection will be sought in the appended claims.

In the drawings:

Fig. 1 is a side elevation of a machine embodying the present invention, some of the parts being broken away for the purpose of clearness of illustration;

Fig. 2 is a perspective view on a large scale showing certain parts for automatically controlling the pressure between the work and the tool, some of the parts being omitted and broken away;

Fig. 3 is an under-side view of the parts shown in Fig. 2, some of the details being broken away.

The machine herein illustrated as embodying the present invention is an automatic burnishing or edge-setting machine wherein the edge-setting tool 10 is carried in the head 11 in which it is vibrated in a substantially horizontal plane to act upon the edge

of a shoe *a*, as indicated in Fig. 1. The head 11 is supported by the link members 12 and 13, the former of which is pivotally connected directly to the pressure lever 14, and the latter of which is also pivotally connected to the pressure lever 14 by means of a bell crank 15 which is itself pivoted to the pressure lever 14 and has its extremities connected to the member 13 and a link 16, the lower end of the link being pivotally connected to the machine frame or a stationary member at 17, as indicated in Fig. 1.

The pressure lever 14 is pivoted to the main frame at 18, the construction being such that rotation of the pressure lever about its pivot 18 will move the edge-setting tool to the right or left, as indicated in Fig. 1. The members 12, 13, 14, 15 and 16 constitute a parallel motion mechanism which may be substantially as more fully described in the patent to Keall, Gouldbourn & Jerram No. 1,078,684, dated November 18, 1913.

The shoe *a* is supported by or clamped in a jack 19, mounted on a shaft 20 which is carried in mechanism which permits it to move in a horizontal plane and to turn about a vertical axis. A cam 21 on the shaft 20 is automatically rotated and translated in a horizontal plane to turn the shoe from one side to the other and keep its edge presented to the edge-setting tool 10.

All the mechanism thus far described may be substantially identical with that shown in the patent mentioned, and reference is made to the patent for a further description and illustration.

A power transmitting element 22, preferably constituted as a universal joint, is connected with the shaft 20 and a cam 23 is suitably supported for rotative movement with the shaft 20 through the universal joint connection 22.

A fulcrum shaft 25 is mounted in suitable bearings 25* formed in the machine frame or parts carried thereby, and has secured thereto the starting or controlling lever 26 and an arm 27, the construction being such that movement of the starting or controlling lever 26 will effect rotative movement of the shaft and corresponding movement of the arm 27. A spring 29 has one end adjustably connected to the arm 27 at 28, Fig. 2, and the other end attached to an arm 30 projecting from a sleeve 31 loosely mounted on the fulcrum shaft 25.

The sleeve 31 has extending therefrom the arms 31* which are connected by suitable links 32 to a rod or plunger 33, the lower end of which works in a dashpot 34, Fig. 1. A rod 35 is secured to the plunger and extends slidably through an abutment 36, Fig. 1, pivotally mounted at 36* on the pressure lever 14. A spring 37 encircles the rod 35 and is confined between the abutment 36 and a collar 38 secured to the rod

35. The purpose of the spring 37, as will hereinafter more fully appear, is to produce pressure between the work and the tool as the two are relatively moved and for the purposes of identification the spring 37 will be hereinafter identified as the "pressure spring". The spring 29 hereinbefore mentioned as extending between the arm 27 and the sleeve 31, is stronger than the pressure spring 37 and for the purpose of identification it may be known as the "compression spring" because, through its action under control of means to be herein-after described, the pressure effect of the pressure spring 37 is increased.

When the starting or controlling lever 26 is turned contra-clockwise, Fig. 1, and Fig. 2, it rocks the fulcrum shaft 25 and arm 27, which, through the spring 29, sleeve 31 and connections, forces the plunger 33 and rod 35 upwardly in Fig. 1 through the abutment 36, thereby placing the pressure spring 37 under compression. The pressure lever 14 is thus actuated through the pressure spring 37 to produce pressure between the tool and the work, such pressure, in the present instance of the invention, being transmitted through the tool.

The starting or controlling lever 26 has a catch 39 for retaining it in position to which it may have been moved by the attendant, and said catch is automatically released when the action of the tool upon the work is completed as described in the patent hereinbefore mentioned. When the starting or controlling lever is thus released, the pressure spring 37 acts to force the plunger 33 back into the dashpot 34, carrying the starting or controlling lever clockwise and slackening off the pressure from the pressure lever 14.

Loosely mounted on the shaft 25 is a second sleeve 40 having an arm 41 carrying a roll 42 which engages the cam 23. An arm 43 on the sleeve 40 extends towards 110 and opposite an arm 44 extending from the sleeve 31, the construction being such that under the impulse of the compression spring 29 the arm 44 will bear against the arm 43 which, through the sleeve 40 and arm 115 41 is responsive to the controlling influence of the cam 23.

In order that the arms 43 and 44 may be properly associated in cooperative relation, one of said arms, in the present instance 120 the arm 44, is provided with an adjustable stud 45 and a set nut, as indicated in Fig. 3, serves to maintain the adjustable stud in fixed adjusted position.

From the construction described it will 125 be evident that when the starting or controlling lever 26 is moved contraclockwise, Figs. 1 and 2, the compression spring 29 will be placed under increased tension to thereby yieldingly turn the sleeve 31 and, 130

perforce, place the pressure spring 37 in pressing relation with its associated parts to produce pressure between the work and the tool. The parts being in the position

5 stated and the machine in operation, should a high part of the cam 23 engage the roll 42 as the cam revolves, the arm 43 will act through the arm 44 to turn the sleeve 31 against the stress of the spring 29 and there-
10 by relieve the pressure exerted by the pressure spring 37 and modify the pressure between the work and the tool. When the high part of the cam has passed the roll 42 the stronger spring 29, acting through its
15 connection with the rod 35, will again restore the pressure spring 37 to its original pressure transmitting position.

The cam 23, as hereinbefore described, rotates with the shaft 20, and its contour will 20 be so designed as to diminish the pressure action of the spring 37 and the corresponding reaction of the pressure lever 14 when the sharply curved portions of the sole edge are presented to the tool 10. The cam 25 23 may be variously contrived with proper contour either to engage the roll 42 only at isolated intervals predetermined by the portion of the work to be treated by the tool, thus leaving the spring 37 compressed by
30 the entire tension exerted by the spring 29 at all other times; or it may be so formed as to engage the roll 42 continuously, thereby effecting a positive continuous control over the action of the stronger spring on
35 the weaker one and correspondingly varying the pressure between the work and the tool.

As the shoe turns from one side to the other, causing relative movement between 40 the sole edge and tool, there will be slight variations in the absolute position of the point of contact of the tool and work. This necessitates slight movements of the tool carrying mechanism, and, in heretofore 45 existing machines, consequent variations in the pressure between the tool and the work. When such irregularities are found to cause noticeable impairment of the quality of work done, which may occur on shoes of extreme
50 style, the cam 23 will be designed to compensate for the lack of uniformity in pressure on those parts of the work and produce uniformity of pressure throughout, or relieve such pressure in whole or in part on
55 any portion of the shoe where the full pressure between the tool and the work is not desired.

Having described my invention, what I claim as new and desire to secure by Letters Patent of the United States is:

1. In a machine of the class described, the combination of a work support, a tool for acting along different portions of the work as the work and tool are relatively moved, means for producing pressure be-

tween the work and tool, and means acting in opposition to the pressure producing means for adapting the pressure between the work and tool to the character of the work.

70

2. In a machine of the class described, the combination of a work support, a tool for acting along different portions of the work as the work and tool are relatively moved, means for producing pressure between the work and tool, and automatic means acting in opposition to the pressure producing means to reduce the pressure between the work and the tool at a predetermined part of the work as the work and tool are relatively moved in contact with one another.

3. In a machine of the class described, the combination of a work support, a tool, pressure producing means acting as the work and tool are relatively moved to maintain pressure between the work and tool, and pressure relieving means acting positively in opposition to the pressure producing means along predetermined portions of the work to vary the pressure between the work and tool during the action of the tool.

4. In a machine of the class described, the combination of a work support, a tool for acting along different portions of the work as the work and tool are relatively moved, a yieldable pressure transmitter for maintaining pressure between the work and tool, and means acting automatically in opposition to the pressure transmitter to modify the pressure between the work and tool along a portion of the work.

5. In a machine of the class described, the combination of a tool for acting along the edge of a shoe, pressure means acting yieldingly through the tool for maintaining pressure between the shoe and tool as they are relatively moved, and pressure relieving means acting automatically to positively inhibit the pressure exerted by the pressure means as the tool moves along a predetermined portion of the shoe.

6. An organized machine for automatically treating shoes, comprising, in combination, a shoe support, a tool for acting along different portions of a shoe on said support, means including a spring for causing pressure between the shoe and tool as they are relatively moved, and means acting automatically to control directly the effective end of the spring as the tool moves along the shoe.

7. In an organized machine for automatically treating shoes, the combination of a tool for acting along portions of the shoe, pressure means including a spring for causing pressure between the shoe and tool as they are relatively moved, a pressure controlling cam, and connections between the cam and pressure means for effecting a positive limit to the pressure between the work

125

120

- and tool along a predetermined part of the work.
8. In a machine of the class described, the combination of a work support, a tool, means for causing pressure between the work and tool as they are relatively moved, a pressure controlling cam and means responsive to the action of the cam to predeterminedly permit increase or positively decrease the pressure exerted by the pressure causing means.
9. In a machine of the class described, the combination of a work support, a tool, a spring for producing pressure between the work and tool as they are relatively moved to present different portions of the work to the action of the tool, a pressure controlling cam, and means responsive to the action of the cam for directly controlling the active end of the spring.
10. In a machine of the class described, the combination of a work support, a tool for acting along the edge of the work, a pressure producing spring acting through the tool to produce pressure between the work and tool, a pressure controlling cam, and connections between the cam and pressure producing spring including a compression spring for changing the pressure of the tool upon the work along different parts of the work.
11. In an automatic edge setter, the combination of a tool for acting along the edge of a shoe, a spring for pressing the tool against the edge of the shoe, a cam, and connections between the cam and spring including a second stronger spring for changing the pressure of the tool against the edge of the shoe along different portions thereof.
12. In an automatic edge setter, the combination of a tool for acting along the edge of a shoe, a pressure spring for pressing the tool against the edge of the shoe, a stronger compression spring, and a cam controlling the action of the compression spring for modifying the pressure of the tool against the shoe.
13. In a machine of the class described, the combination of a work support, a tool for acting along different portions of the work, a pressure spring for causing pressure between the work and tool as they are relatively moved, a stronger spring normally tending to increase the power of the pressure spring, and means acting in opposition to the stronger spring to decrease the power of the pressure spring along predetermined portions of the work.
14. In a machine of the class described, the combination of a work support, a tool, means for exerting a yielding pressure between the work and tool as they are relatively moved to present different portions of the work to the tool, means operable at will for placing the yielding pressure means in pressure exerting position, a spring normally tending to increase the pressure of the yielding pressure means, and a cam acting in opposition to the spring for modifying the pressure along a predetermined part of the work.
15. A machine of the character described, comprising, in combination, a tool for treating different portions of a shoe, pressure means for producing pressure between the shoe and tool as they are relatively moved to present different portions of the shoe to the tool, means operable by the attendant for placing the pressure means in position to exert pressure, a spring tensioned by the attendant and tending to increase the pressure exerted by the pressure means, and a cam acting automatically as the tool moves along a predetermined part of the shoe to change the pressure between the shoe and tool.
16. In a machine of the class described, the combination of a tool for acting along the edge of a shoe, a spring for pressing the tool against the edge of a shoe, having one end connected with the tool, a movable abutment to which the other end of the spring is connected, a second and stronger spring having one end connected to the abutment and the other end anchored, whereby stress may be transmitted from the stronger spring to the other spring through the abutment, and a cam and connections for controlling the abutment to regulate the stress transmitted from the stronger spring.
17. In a machine of the class described, a tool for acting along the edge of a shoe, and means for pressing the tool and shoe together comprising a stronger and a weaker spring arranged in tandem, and means for predeterminedly positioning the junction point of the springs, whereby the stress transmitted from the stronger to the weaker can be controlled.

In testimony whereof I have signed my name to this specification.

JOHN H. RIGBY.
